WEST PHILAD STOVE WORKS
PATENTED 1855

Res. 757

1

Garrettson Smith, Henry Brown, and
Joseph A. Read, of Philadelphia, Penna

Assignors to

A. E. Warfield, of same place

Letters Patent No. 757, Dated Jan. 22, 1856

Ante-dated Dec. 31, 1853.

The schedule referred to in these Letters Patent, and making part of the same. —

To all whom it may concern:

Be it known that we Garrettson Smith, Henry Brown, and
Joseph A. Read, of the City and County of Philadelphia, and State of Pennsylvania,

have produced a new and original design for oval portable furnaces, and we do hereby declare that the following is a full, clear and exact description of the same, reference being had to the annexed drawing forming part of this specification, in which —

Figure 1. is a top view of the furnace.

Figure 2. is a front elevation.

Figure 3. is a plan of hearth. —

Similar characters of reference in the several figures denote the same part of stove & design.

The body A. of the furnace which is of oval cross section, tapers slightly upward until the part B. is reached, which swells outward as shown in the drawing and supports the top plate C. The body of the furnace is ornamented with the flutes f. running from the projecting top portion of the small molding D. which joins the base plate E. except those above the door, which extend only to the molding on, at the top of the door, the door itself being ornamented in the same manner. —

The top plate C. is of the form shown in the drawing, plain on the top and bordered by a curved edge overhanging the body of the stove, and ornamented in bas-relief as shown in the drawing. —

The base plate E. supports the body of the stove and forms the hearth. It bears the inscription "West Phila. Stove works Patented 1855," in raised capitals and numerals, and has a hollow concave edge flaring downward, upon which at regular intervals are the bas-relief projections h. arranged as shown in the drawing. —

The design configuration and arrangement of the several parts being as shown in the drawing. —

What we claim as our production and desire to secure by Letters Patent, is the design configuration and arrangement of the several plates and ornaments thereon, as herein set forth and shown in the drawing, constituting a new design for portable furnaces. —

In testimony whereof we have hereunto signed our names before two subscribing witnesses.

Witnesse.
